US00D454780S

(12) **United States Design Patent**
Leboeuf et al.

(10) **Patent No.:** **US D454,780 S**
(45) Date of Patent: **** Mar. 26, 2002**

(54) **CONTAINER**

(75) Inventors: **Joseph Leboeuf**, Saint-Martin-De-Ré (FR); **Justin E. McDonough**, Kenvil, NJ (US)

(73) Assignee: **Pechiney Plastic Packaging, Inc.**, Chicago, IL (US)

(**) Term: **14 Years**

(21) Appl. No.: **29/121,543**

(22) Filed: **Apr. 6, 2000**

(57) **CLAIM**

The ornamental design for a container, as shown and described.

DESCRIPTION

FIG. 1 is a top perspective view of a container showing our new design, the helical thread extending about the neck of the container being shown in broken lines for illustrative purposes only and forming no part of the claimed design; FIG. 2 is an enlarged view, with portions broken away, of the top portion of the container of FIG. 1; FIG. 3 is a top view of the container of FIG. 1; FIG. 4 is a bottom view of the container of FIG. 1; FIG. 5 is a front view of the container of FIG. 1, the rear view of which is identical to the front view thereof; and, FIG. 6 is a right side view of the container of FIG. 1, the left side view of which is identical to the right side view thereof.
